(57) **CLAIM**

The ornamental design for a security face plate for cabinet lock, as shown and described.

DESCRIPTION

FIG. 1 is a top right perspective view of a security face plate for cabinet lock showing my new design.

FIG. 2 is a front elevational view thereof.

FIG. 3 is a right side elevational view thereof.

FIG. 4 is a rear elevational view thereof.

FIG. 5 is a top plan view thereof.

FIG. 6 is a top right perspective view of a second embodiment of the design shown in FIG. 1.

FIG. 7 is a front elevational view of the second embodiment of the design.

FIG. 8 is a right side elevational view of the second embodiment of the design.

FIG. 9 is a rear elevational view of the second embodiment of the design; and,

FIG. 10 is a top plan view of the second embodiment of the design.
